US0D1077242S

(12) **United States Design Patent** (10) **Patent No.:** **US D1,077,242 S**
(45) **Date of Patent:** **** May 27, 2025**

(54) **WRISTBAND**

(71) Applicant: **Shenzhen Qijiang Technology Co., Ltd.**, Guangdong (CN)

(72) Inventor: **Chengxiang Li**, Guangdong (CN)

(73) Assignee: **Shenzhen Qijiang Technology Co., Ltd.**, Guangdong (CN)

(**) Term: **15 Years**

(21) Appl. No.: **29/900,862**

(22) Filed: **Aug. 25, 2023**

(51) LOC (15) Cl. **24-04**

(52) U.S. Cl.

USPC **D24/190**

(57) **CLAIM**

The ornamental design for a wristband as shown and described.

DESCRIPTION

FIG. 1 is a front, right and perspective view of a wristband, showing my design.

FIG. 2 is a front, left and perspective view thereof.

FIG. 3 is a top perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof; and,

FIG. 10 is an enlarged view of detail 10 in FIG. 1.

The dot-dash broken lines in FIG. 10 depict the boundaries of the enlargements that form no part of the claimed design.

1 Claim, 10 Drawing Sheets
